UNITED STATES PATENT OFFICE.

CHARLES M. HUNSICKER, OF DAYTON, OHIO.

FLYING-MACHINE.

1,227,269.

Specification of Letters Patent. Patented May 22, 1917.

Application filed July 12, 1916. Serial No. 108,774.

To all whom it may concern:

Be it known that I, CHARLES M. HUNSICKER, a citizen of the United States, residing at Dayton, in the county of Montgomery and State of Ohio, have invented certain new and useful Improvements in Flying-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to flying machines, and particularly to flying machines of the combined aeroplane-helicopter type, the object of the invention being to provide a flying machine of this character which is simple of construction, reliable and efficient in action, and embodies a minimum number of working parts, as will hereinafter more fully appear.

A further object of the invention is to provide a flying machine having a supporting surface formed of sustaining planes which may be readily and conveniently furled or reefed when it is desired to reduce resistance to ascension or descension, and which may be unfurled or unreefed for use when it is desired to employ an aerofoil or sustaining surface.

With these and other objects in view, the invention consists of the features of construction, combination and arrangement of parts hereinafter fully described, and claimed reference being had to the accompanying drawings in which Figure 1 is a top plan view of the machine with the wings or sustaining planes spread; Fig. 2 is a side elevation of the machine with parts broken away to facilitate clearness; Fig. 3 is a vertical longitudinal section through the machine, on the line 3-3 of Fig. 2; Fig. 4 is a vertical transverse section on the line 4-4 of Fig. 2; Fig. 5 is a vertical transverse section on the line 5-5 of Fig. 2.

In carrying my invention into practice, I provide a main frame 1, which is shown in the present instance as substantially of oblong rectangular form and provided with tapered or V-shaped bow and stern portions 2 and 3. The machine is shown as provided with lugs 4 for supporting the same on wheels 4^a when at rest upon the ground sur-

face, but it may be provided with any other suitable type of launching and alighting gear for land or marine use.

Arranged at the front and rear of the machine are vertical shafts 5 and 6 which extend to a desired elevation above the framework and carry fore-and-aft lifting and sustaining propellers 7 and 8. These propellers may be of any suitable construction and are employed in practice to lift the machine for straight ascensions, for supporting the machine at a desired elevation so as to hover above any point of the surface of the earth below, and for controlling the speed of descent of the machine, all of which actions may be obtained by driving said propellers at different rates of speed. The shafts 5 and 6 are journaled in suitable bearings and shaft 5 is provided with a beveled gear 9 which meshes with a transmission gear 10 on a transverse transmission shaft 11, which shaft 11 carries a sprocket wheel 12, connected by chain 13 with drive sprocket 14 upon an end of the shaft of a centrally disposed motor 15. The propeller 8 is driven from the shaft 5 by sprocket chain 38 and sprockets 39 mounted on the shafts 5 and 6. The rotation of the propellers 7 and 8 is controlled by a clutch 33 connected by a rod 34 to a lever 15 adjacent to the seat 21 and operated by the aviator.

For the purpose of driving the machine in straightway flight, a tractor propeller 16 is provided, the same being mounted upon the outer end of a horizontal longitudinally extending shaft 17 which carries a pinion 18 meshing with a gear 19 on a shaft 40. The shaft 40 is mounted in suitable bearings and is connected through a clutch 20 to a sprocket 42 which in turn is connected to a sprocket 43 of the engine by a chain 44. The clutch 20 is controlled by a lever 22 connected thereto by a rod 46.

Supported by the frame in proximity to the bow portion thereof are laterally projecting arms or wing spars 23. Each is centrally united and fastened to the frame, which spars support the forward portions of triangular wings or planes 24. These wings or planes, which are preferably in the form of right angle triangles, have their bases forwardly disposed, their straight sides arranged in proximity and in parallel relation to the sides of the main frame and their inclined sides outwardly disposed, the said

base portions of the wings being provided with hems or pockets 25 which slidably receive and engage the wing spars 23, the reduced or apex portions of the wings being secured to the main frame, as indicated at 26. These wings 24 when unfurled or spread provide a supporting or aerofoil surface to furnish with the frame and tractor a motor driven gliding structure for straightway travel in the air, the wings also serving, when desired, as braking surfaces to reduce the speed of descent in downward travel. In starting the flight, the machine is driven upwardly by means of its lifting and sustaining propellers, which are operated at high speed, during which time the wings are furled or reefed, but as soon as the desired altitude is reached the speed of the lifting propellers may be reduced and the driving propeller thrown therewith into action, the driving propeller being driven at its normal traction speed to adapt the lifting propellers to act in conjunction with the wings as sustaining elements, the wings being, as soon as the machine is started in straightway flight, spread to serve as sustaining surfaces.

Suitable means are provided for furling and spreading the wings at will, that shown in the present instance consisting of a pair of ropes or cables 27 and 28, connected with the forward portion of each wing at 41, which cables pass over the guide pulleys 29 and are connected to wind and unwind in opposite directions on drums 30 upon a crank shaft 31 which is operated from the crank portion 32 thereof. The sets of cables of the two wings are connected to different drums for conjoint operation, whereby when the control crank 32 is turned in one direction both wings will be spread while when said control crank is turned in the opposite direction both wings will be furled. In the furling and unfurling motions of the wings, the pocket portions 25 thereof slide inward and outward on the wing spars 23, as will be readily understood.

It will be seen from the foregoing description that a machine is provided which partakes of the properties and advantages of both the aeroplane and the helicopter, and which in the event of damage to its wings or tractor propeller may still be sustained in the air and brought to a safe landing. The

machine is also capable of being driven ahead with considerable speed while being supported by the lifting propellers, and may be caused to ascend or descend directly at a greater or less speed without tilting the machine to an upwardly or downwardly inclined angle to its normal flying position. These and other advantages will be apparent. A vertical rudder 35 is arranged at the rear of the main frame and connected by cables 36 with a control wheel 37 whereby the machine may be steered laterally in an obvious manner by turning said wheel.

Having described my invention, I claim.

1. In a flying machine, the combination of front and rear lifting and sustaining propellers mounted on vertical shafts, a forward driving propeller mounted horizontally, a motor, a transmission shaft geared to the shaft of the rear lifting and sustaining propeller, a transmission shaft geared to the forward driving propeller, a chain drive connecting the motor shaft with the transmission shaft of the rear lifting and sustaining propeller, a chain drive connecting the shaft of the rear lifting and sustaining propeller with the shaft of the front lifting and sustaining propeller, and a chain drive connecting the motor shaft with the shaft of the forward driving propeller, substantially as described.

2. In a flying machine, a main frame, forward and rearward lifting and sustaining propellers, a forward driving propeller, wing spars extending laterally from the forward portion of the frame, triangular sustaining wings mounted at opposite sides of the frame and extending from the forward to the rearward lifting and sustaining propellers, the forward edges of said triangular sustaining wings being provided with pockets which receive the wing spars and are thereby supported in a position to be extended or reefed, and cables connected with said wings for operating the same, substantially as specified.

In testimony whereof I affix my signature in presence of two witnesses.

CHARLES M. HUNSICKER.
